CLAIM

The ornamental design for a shoe, as shown and described.

DESCRIPTION

FIG. 1 is a front, left, and top perspective view of a shoe showing our design.

FIG. 2 is a rear, right, and bottom perspective view thereof.

FIG. 3 is a left side view thereof.

FIG. 4 is a right side view thereof.

FIG. 5 is a rear view thereof.

FIG. 6 is a front view thereof.

FIG. 7 is a top view thereof.

FIG. 8 is a bottom view thereof; and,

FIG. 9 is an enlarged view thereof, taken from encircled portion "9" in FIG. 5.

The even-dash broken lines in the drawings illustrate portions of the shoe that form no part of the claimed design. The dot-dash broken lines in FIG. 5 and FIG. 9 are for reference purposes only to identify the area of the enlargement. The dot-dash broken lines in FIG. 5 and FIG. 9 form no part of the claimed design.
